CUSHION FOR A BEDPAN

Hope E. Souza, 3423 Motor Ave., Los Angeles, Calif.

Filed July 10, 1964, Ser. No. 80,793

Term of patent 14 years

(Cl. D4—5)

FIG. 1.

FIG. 2.

FIG. 3.

FIG. 1 is a front, side and top perspective of a cushion for a bedpan, showing my new design.

FIG. 2 is a bottom plan view thereof.

FIG. 3 is a rear elevational view thereof.

The right-hand side of the cushion is a substantial duplicate of the left-hand side shown in FIG. 1 except for omission of the air valve. The bedpan shown in broken lines is for illustrative purposes only.

I claim:

The ornamental design for a cushion for a bedpan, as shown and described.
